(57) **CLAIM**

The ornamental design for a linear stapler design, as shown and described.

DESCRIPTION

FIG. 1 is perspective view of the linear stapler design;
FIG. 2 is a top plan view of the linear stapler design;
FIG. 3 is a left side view of the linear stapler design, the right side being a mirror image;
FIG. 4 is a bottom plan view of the linear stapler design;
FIG. 5 is a front end view of the linear stapler design; and,
FIG. 6 is a rear end view of the linear stapler design.
The broken lines shown in the drawings represent portions of the linear stapler design that form no part of the claimed design.
